O. A. GRIDER

RAIL JOINT

Filed Feb. 5, 1924

FIG. 1.

FIG. 2.

FIG. 4.

INVENTOR.
O. A. Grider,

BY
Geo. P. Kimmel
ATTORNEY.

UNITED STATES PATENT OFFICE.

ORVILLE A. GRIDER, OF VANDALIA, ILLINOIS.

RAIL JOINT.

Application filed February 5, 1924. Serial No. 690,753.

To all whom it may concern:

Be it known that I, ORVILLE A. GRIDER, a citizen of the United States, residing at Vandalia, in the county of Fayette and State of Illinois, have invented certain new and useful Improvements in Rail Joints, of which the following is a specification.

This invention relates to rail joints, and has for its primary object the provision 10 in a manner as hereinafter set forth, of a railroad joint so constructed that vibration and lateral movement of the rails at their meeting ends is greatly reduced.

Another object of the invention is the provision in a manner as hereinafter set forth, of a railroad joint so constructed that the meeting ends of the rails have their tread and web in overlapping relation, thus 15 eliminating any chance, in the event that 20 the fish plates become broken, of the rails shifting and becoming out of alinement.

Another object is the provision, in a manner as hereinafter set forth, of a rail joint so set up as to provide for expansion and 25 contraction of the rails, under varying climatic conditions, without the formation of excessive spaces transversely of the rail.

The final object is the provision in a manner as hereinafter set forth, of a railroad 30 joint which will be as strong as the main body of the rail, of a structure easy to pass, easily assembled, and inexpensive to construct.

In the drawings:

Figure 1 is a top plan view of the rail 35 joint embodying this invention.

Figure 2 is a side elevation thereof.

Figure 3 is a transverse sectional view taken upon the line 3—3 of Figure 1, and,

Figure 4 is a detail perspective view of 40 one end of one of the rails showing the manner in which the end is molded to fit into a correspondingly molded end of another rail.

Referring now to the drawing in detail 45 wherein like numerals of reference indicate corresponding parts throughout the several views of the drawing, there are shown the abutting ends of two sections of rail of the usual construction and consisting of the head 1, the web 2 and the base 3. The usual bolt holes 4 are formed through the web of each 50 of the rails.

The end of each rail section at each end

has its foot finished off at right angles to 55 the length of the rail forming the transverse vertical abutting end 5. The head and the web portion of each end of the rail is divided through its longitudinal center, and the web and head upon one side of this central longitudinal division is removed and the cutout portion extends rearwardly of the transverse abutting end 5 while upon the other side of this central longitudinal division the web and head are extended forwardly of the 60 end 5 as follows: The web upon one side of the central division is cut backwardly and upwardly to form the shoulder 6 until the underside of the head 1 is reached whereupon the head is finished off to provide the 65 vertical lateral shoulder 7. The other half of the web upon the other side of the central longitudinal division referred to extends outwardly and upwardly at an inclination from the wall 5 as at 8 and where it merges 70 into the underside of the head at the other end of the inclined portion the tread terminates in the vertical abutting wall 9. From this method of formation of the end 75 of the rail it will be seen that there is provided a substantially triangular shaped extension 10 formed of one-half of the web and the head of the rail and overlapping and abutting a similarly formed angled shaped extension of an abutting rail. The angles 80 of the inclined shoulders 6 and 8 are the same and the formation of each end of each rail section is the same with the exception that at one end the extension of the web forward of the end 5 and of the head is 85 upon one side whereas at the other end it is upon the opposite side. The purpose of this is apparent.

When the rail ends are placed together the ends 5 of the rails abut, the faces of 90 the angle shaped overlapping extensions 10 abut and the extended end 9 of the head of one rail abuts the vertical shoulder 7 in the head of the other rail and the inclined surface 8 of one of the rails rests 95 upon the inclined shoulder 6 of the adjoining rail. Thus the rails, in a way, automatically aline themselves and when so alined fish plates 11 are placed one on either 100 side of the web 2 in a position to overlap the joints and bolts 12 are passed through the apertures 4 in the webs of the rail and through similar apertures in the fish plates 105

11 whereupon nuts 13 are applied to the bolts and tightened to draw the fish plates tightly against the overlapping webs.

From the foregoing description it may be readily seen that there is provided an improved rail joint so constructed that due to the overlapping relation of the rail ends there is, in a way, a locking action between the rail ends which will prevent undue rattling and movement of the rails and further, in the event that the fish plates 11 should become broken, as is often the case, the rails will not shift their position, nor can either rail end sag for in this case if there was any tendency to sag the sagging rail would be supported upon the end of the adjacent rail due to the overlapping of the shoulders 6 and 8 of the opposed rails.

As a result of constructing a rail joint in the above described manner the strain on the fish plates is greatly decreased thus materially increasing the strength and efficiency of the joint as a whole.

While the drawing and description set forth the preferred embodiment of my invention still it is to be understood that the invention is not confined to any strict conformity to the showing of the drawing, but may be changed and modified so long as such changes and modifications mark no

material departure from the salient features of the invention as expressed in the appended claim.

Having thus described my invention, what I claim is:

A rail joint comprising in combination, a pair of opposed track rails, the opposed end terminal portions of said rails each having its web and head cut inwardly from one side through one-half their thickness to form the head with a vertically disposed lateral shoulder extending from the top to the bottom thereof, and the web with an upwardly inclined shoulder extending from the lower free end of the web and terminating at the lower edge of the shoulder on the head, each of said rails further provided with a substantially triangular shaped extension integral with the head and web and forming a lengthwise continuation thereof, the extension of one rail positioned in parallelism with the head and web of the other rail, the end and under edge of said extensions further opposing said shoulders, a fish plate positioned against the outer faces of the extensions, and means for securing the fish plates and rails together.

In testimony whereof, I affix my signature hereto.

ORVILLE A. GRIDER.
